UNITED STATES PATENT OFFICE.

ORLAN S. VANCAMP, OF KANSAS CITY, MISSOURI.

FRESH-AIR BED.

1,251,846.

Specification of Letters Patent.

Patented Jan. 1, 1918.

Application filed April 22, 1915. Serial No. 23,044.

To all whom it may concern:

Be it known that I, ORLAN S. VANCAMP, a citizen of the United States, residing at Kansas City, in the county of Jackson and 5 State of Missouri, have invented certain new and useful Improvements in Fresh-Air Beds, of which the following is a full, clear, and exact description, such as will enable others skilled in the art to which it appertains to make and use the same.

The invention relates to fresh air beds and seeks to provide an improved form of bed that may readily be extended from a building through a door or window and as easily 15 drawn to the interior of the building when desired, the movement from the interior to the exterior or the reverse movement requiring but a moment of time.

Many forms of tents, sleeping porches and 20 the like have been devised for sleeping in the open air, and air shafts connecting to beds indoors have been employed, the advantages of fresh air for promotion of health being generally recognized by physicians as well as the general public.

In crowded cities the tent and sleeping porch cannot be generally used owing to the lack of room, and the air shafts connecting to beds inside the building are not equivalent to the open air, their result often being 30 harmful instead of beneficial. A bed that may remain inside the building during the day and be extended at night and which may immediately be drawn into the building in case of high wind or storm will possess advantages over the sleeping porch or tent in that it may be immediately converted from an open air to a protected bed. A bed constructed in this manner may serve all 35 who desire open air whereas under the present conditions very few of the general public are in a position to avail themselves of open air sleeping quarters.

The present invention seeks to provide an 45 improved bed which may be occupied without or within a building at the pleasure of the occupant and which may be practically instantaneously shifted from either location to the other.

50 The invention consists in the improved features of construction, combinations and arrangements of parts hereinafter set forth, illustrated in the accompanying drawings and more fully pointed out in the claims 55 hereunto appended.

In the drawings:—

Figure 1 is a view in elevation of the improved bed and a fragmentary sectional view of a building to which the bed is attached, the bed being shown in extended position outside the outer wall of the building.

Fig. 2 is a fragmentary exterior view in elevation of the building, a window casing, a pair of hinged window sash, and an end view in elevation of the bed.

Fig. 3 is a fragmentary sectional view of the bed supporting connections taken on line *a* of Fig. 1.

Fig. 4 is a fragmentary sectional view taken on line *b* of Fig. 1.

Fig. 5 is a fragmentary sectional view taken on line *c* of Fig. 1.

Fig. 6 is a fragmentary sectional view taken on line *d* of Fig. 5.

The walls 1 and 2, ceiling 3, casing 4, 5, 6 and 7 and the swinging window sash 8 are of usual and well known construction such as may be employed in the construction of any dwelling or hotel.

To the window casing 4 is secured by 80 screws 9 the block 10, to which is secured in any usual manner the angle shaped bars 11 which extend outward from the wall 1 preferably the distance of the full length of the bed and slightly beyond and inside the 85 wall a sufficient distance to allow the bed to be fully withdrawn to the inside of the wall, the wall 2 being broken away because of insufficient room for fully illustrating and because of well known construction.

Between the inner end 12 of the angle shaped bars 11 and the ceiling 3 is a bridge 13 to hold the inner end of the bars down so that the outer end 14 will stand rigid and support the weight of the bed and any 95 person or persons that may occupy the same, the flanges 15 of the angle shaped bars forming a track for the wheels 16 to roll upon, and underneath which the roller 17 is secured in rolling position to remove any friction that may be caused by a tipping or 100 tilting of the bed, the wheels 16 being journaled on the pins 18 which are riveted to the yoke 19, the yoke extending downward from each of the wheels 16 and connecting integrally underneath the flanges 15, the pin 20 passing through the yoke and forming a journal for roller 17 to roll upon.

From the foregoing it will be understood that there are two of the yokes 19 and that 110

each yoke in connection with the wheels 16 and roller 17 form a truck that will roll freely along the flanges 15 of the angle shaped bars 11, each yoke supporting one 5 end of the bed.

To the yokes 19 are secured by rivets 21 the angle shaped bars 46 to which are secured in any convenient manner the corner posts 22, the latter extending downward and 10 being connected by intermediate end rails 23, lower end rails 24, and lower side rails 25 which are pivotally connected at their ends by pins 26 to posts 22 and are connected by auxiliary posts 27 to the rails 28.

15 The rails 28 are preferably tubular and in them are inserted pairs of latch rods 29 separated by springs 30, the rods being provided with handles 31 extending downward through the slotted hole 32, the outer ends 47 20 of the latch rods engaging the posts 22 and being held in engaged position by the spring 30, the handles serving as a means of disengaging the rods from the posts so that the rails 28 may be lowered as indicated by the 25 view Fig. 5 for the purpose of easy access to the bed.

The floor 33 is provided to retain any usual form of bedding and it may also serve as a support for seats as common chairs and 30 the like to afford a cool place to spend the evening, the floor being merely a flat plate of metal or wood secured in any usual manner.

35 Journalized in the posts 22 is the shaft 34 to which is secured the bevel gear 35, in which meshes the bevel gear 36, the latter being journalized on the pin 37 secured to bracket 38 shown in dotted lines behind the gear 36 in Fig. 2 and, in turn secured to the 40 intermediate cross rails 23. Upon the shaft 34 is mounted the drum 43 from which leads the cord or cable 54 in one direction upward and over the pulley 39 and then to the end 14 of the angle shaped bars 11 where it is 45 secured to the spool 40, the opposite end of the cord extending upward and over the pulley 41 and then to the end 12 of the angle shaped bars 11 where it is secured to the spool 42, the pulleys 39 and 41 being mounted 50 to revolve on the pin 44 by which they are secured to the yoke 45 the latter in turn being secured to the angle shaped bars 46.

From the foregoing it will be understood that the bed is mounted to traverse the angle 55 shaped bars 11 and that the floor 33 is supported by posts 22 through connections to wheels 16, the floor forming a suitable place on which to arrange seats or bedding, and

that the occupant may by turning the windlass 34 with handle 48 and gears 35 and 36 60 easily move the bed from the interior of the wall to the exterior or in the reverse direction, the advantage of this being the ease with which a person may prepare and enter the bed from the interior and then move the 65 bed to the exterior, also in case of sudden storm the bed may as easily and quickly be moved to the interior.

The angle shaped bars 46 are covered by the canvas 49 forming a roof or cover immediately underneath the edge of which are mounted the usual form of roller curtains 50, the curtains not being further illustrated because of well known construction, the curtains being provided with button holes 51 70 positioned to button to the buttons 52 when the curtains are lowered, so that the bed may be entirely inclosed and answer all purposes of a sleeping tent or an inclosed sleeping porch. 75

The blocks 53 are provided and secured in any usual manner to the angle shaped bars 11 to stop the wheels 16 and prevent the bed from being moved too far from the wall 1 so that the wheels cannot be run entirely to 85 the end 14 of the bars and dropped therefrom, the blocks serving as a safety stop.

The improved bed is of chief importance as a fresh air sleeping bed but may also be advantageously employed as a resting place 90 day or night without bedding, the construction being suitable for installation in any building where there is room outside the wall to extend the bed. It is obvious that numerous changes may be made in the details as set forth without departure from the 95 essentials of the invention.

What I claim as new, and desire to secure by Letters Patent, is:—

In fresh air beds, the outer wall of a 100 building, a window opening in said wall, a track secured to said wall in the upper side of said window opening, said track extending into the building and outward from said wall, wheel supported trucks mounted on 105 said track, posts depending from said trucks, bottom frame members connecting said posts, intermediate frame members connecting said posts, and a floor positioned between the lower end of said posts. 110

In testimony whereof I affix my signature in the presence of two witnesses.

ORLAN S. VANCAMP.
